MATRIX MAGAZINE FOR LINECASTING MACHINES

Walter E. Kerschbaum, Wellsboro, Pa., assignor to Mergenthaler Linotype Company, a corporation of New York

Filed Feb. 14, 1962, Ser. No. 173,264
4 Claims. (Cl. 199—44)

This invention relates to linecasting machines wherein matrices, stored end to end in a channeled magazine, are released therefrom by suitably actuated escapement devices and then composed side by side in line. After composition, the matrix line is transferred to the face of a slotted mold, the mold filled with molten metal to form a slug against the matrices which produce type characters thereon, and the matrices thereafter returned by a distributing mechanism to the magazine from which they started.

The magazines as now used in commercial machines, being made largely of brass or even of aluminum plates with steel bracing bars, are quite heavy and difficult to handle in their application to and removal from the machine. In addition, they are complex assemblies comprising a great many parts and subassemblies which contribute to the relatively high manufacturing cost of magazines.

It is, therefore, the object of this invention to substantially reduce the weight of such magazines. It is a further object of the invention to simplify the manufacture of the magazines so as to lessen the cost thereof. It is another object of the invention to provide an improved escapement cover and locking bar mechanism.

In carrying out the invention there is provided a magazine having grooved top and bottom plates formed of aluminum reenforced with cross bars and a longitudinal bar also formed of aluminum. Moreover, the grooved top plate has been lengthened so as to obviate the need for a grooved escapement cover. The escapement cover assembly has been modified so that the matrix locking bar in addition to blocking the matrices in the magazine also pushes the matrices up and away from the verge plungers.

Features and advantages of the invention may be gained from the foregoing and from the following description of a preferred embodiment thereof.

In the drawings:

FIG. 1 is a top plan view of a matrix magazine for a linecasting machine;

FIG. 2 is a fragmentary section taken on line 2—2 of FIG. 1;

FIG. 3 is a side elevational view of the magazine;

FIG. 4 is a fragmentary top view of a magazine showing particularly the escapement cover and matrix locking bar;

FIG. 5 is a front elevational view of the magazine showing details of the escapement cover and matrix locking bar;

FIG. 6 is a fragmentary side view showing the escapement cover and matrix locking bar;

FIG. 7 is a sectional view taken on line 7—7 of FIG. 3; and

FIG. 8 is a sectional view taken on line 8—8 of FIG. 3.

The magazine shown in the drawings comprises a top plate 10, a bottom plate 11, and side bars 12 extending lengthwise of the magazine and serving to separate the top and the bottom plates. The upper end of the magazine (as shown in FIG. 1) is open to permit the entrance of matrices into the magazine. On their inner faces, the plates 10 and 11 are formed with longitudinally extending grooves 13 wherein the customary projecting ears of the matrices engage and whereby the matrices, e.g., matrix 9, are guided in their passage through the

2

magazine. The top and the bottom plates are made of aluminum and are anodized so that they do not exhibit undue wear from the sliding matrices with which they come in contact. The side bars 12 also are made of aluminum. A cover 14, hinged on studs 15, is provided for closing the end of the magazine when it is not in use. In this way dirt and particles are prevented from settling in the magazine and interfering with the movement of the matrices in their grooves.

10 A matrix guard 16 has a plurality of tines 17 projecting from a backing strip 20. The guard is arranged so that the tines 17 extend through apertures 21 formed in top plate 10. The function of the guard is to prevent the sidewise entrance of matrices into the magazine. In other words, the matrices can only enter the magazine if they are upright and their projecting ears are aligned with the plate grooves 13. The guard is formed of a one piece stamping as compared to the past practice of assembling it from a backing strip with individual tines mounted thereon.

On the underside of the magazine, the bottom plate is provided with a number of cross bars, one 22 near the upper end, one 23 near the lower end, and three intermediate ones 24, 25 and 26, which several bars are fastened to the magazine structure by means of bolts 27 passing through top plate 10, side bars 12, bottom plate 11 and the cross bars themselves. The cross bar 24 is extended at its opposite ends beyond the side edges of the magazine to serve as a support for the magazine in applying it to or removing it from the machine, all as well understood in the art. A longitudinal central bar 30 is fixed to the cross bars to aid in guiding the magazine to and from its seat in the magazine frame of the machine. Both the cross bars and the central bar are made of aluminum.

At the lower extremity of the magazine an additional pair of aluminum trapezoidal shaped bars are secured to the side bars 12. These bars, end bar 31 and intermediate bar 32, serve to locate the magazine, when placed in the machine, with respect to the escapement mechanism 33 permanently mounted in the machine and shown in phantom section in FIGS. 7 and 8. The upper surfaces of the bars are grooved so that the matrices are guided until they leave the magazine. The bars will be located by pins 34 and 35 so that the grooves therein are aligned with the grooves of bottom plate 11. A bolt 36 passing through side bar 12 (as well as one passing through the other side bar) secures bar 32 to the magazine. Similarly bolt 37 secures bar 31 to the magazine.

50 An escapement cover 40 is shown fastened to the top plate 10 of the magazine by a bolt 41 which passes through plate 10 in to side bar 12. It will be observed that top plate 10 extends nearer to the end of the magazine than bottom plate 11. In this manner the grooves of the top plate serve to guide the matrices substantially to their exit from the magazine and the need for a grooved escapement cover is obviated. In fact, the present invention contemplates an extruded aluminum cover. The forward edge of the escapement cover is secured to the magazine by bolt 37 which passes therethrough in securing bar 31 to the magazine. Filler pieces 42, which are only as wide as the side bars 12, are placed between cover 40 and side bars 12.

65 The cover 40 serves as a housing for the matrix locking bar 43 which blocks the matrices in the magazine when it is removed from the linecasting machine. When the magazine is in use, the bar is elevated out of the path of the matrix ears and the matrices are held in the magazine until their selected release therefrom by the pawls 44 of the escapement verges. The pawls are shown in dotted line but their function and operation are well known to those skilled in the art. However, when a

magazine is to be removed from the machine the pawls, which are part of the escapement mechanism that remains on the machine, no longer can hold the matrices in the magazine and it is necessary to move locking bar 43 into position to block exit of the matrices. This again is a well known requirement.

The present locking bar is provided with a pair of dowels 45 that project from the bar and extend through elongated slots 46 provided in escapement cover 40. The arrangement is such that as the bar moves from left to right it is elevated out of the path of the matrices. Also, by virtue of the recesses 47 formed in the front edge of the bar and abutments 48 placed on the inside of cover 40 the bar moves forwardly (to the right in FIGS. 7 and 8) under the weight of the matrices as it moves from left to right. Conversely, as the bar moves from right to left as it would when the matrices are being locked therein preparatory to the magazine being removed from the machine, the bar descends to a position blocking the ears of the matrices. At the same time as the recesses 47 move out of engagement with abutments 48 the matrices are moved away from the escapement pawls 44. Thus when a magazine is replaced on a machine there is no danger of the matrices damaging the escapement pawls when the magazine is being seated.

To prevent an inadvertent movement of the locking bar to a matrix unblocking position a latch mechanism is provided. This means that a conscious effort has to be made to move the bar from left to right. The latching mechanism is shown in FIG. 4. A pin 50 projecting from the top of bar 43 cooperates with the irregularly shaped slot 51 of latch 52. The latch is formed at the end of one arm of U-spring 53, the other arm of which is secured to the top of cover 40 by rivets 54. An upstanding flange 55 on latch 52 enables the latch to be moved upwardly (FIG. 4) whereupon bar 43 can be moved towards the right by means of the knob 58 formed on the bar. Bar 43 can be moved to the left without actuating latch 52 since such movement only acts to lock the matrices in the magazine. However, if the locking bar 43 were to be inadvertently moved from a locking position (as shown in FIG. 4) rightwardly to an unlocking position when the magazine is out of the machine an entire font of matrices, i.e., upwards of one thousand individual matrices, would be spilled onto the floor. Consequently, a latching mechanism is provided as described.

As a double safety mechanism, the bar 43 cannot be moved to the right even if latch 42 is actuated since the bar will still be locked in its matrix blocking position by the engagement of a second latch 56 and dowel 45. The second latch 56 is also formed on one arm of a U-spring 57, the other arm of which is fastened to the rear of cover 40 by rivets 58. The shape of the slot 60 in latch 56 is such that the bar cannot be moved rightwardly unless the latch is raised. This is accomplished in operation by the action of plunger 61 which passes through side bar 12. The arrangement is such that when the magazine is seated in the magazine frame of a linecasting machine the plunger is engaged by the escapement mechanism and pushed upwardly against the latch, thereby releasing the latch. Now actuation of latch 56 allows bar 43 to be

moved rightwardly thus unblocking the matrices to permit their release from the magazine under control of the escapement pawls.

It is to be understood that many variations and apparent changes could be made in the preferred embodiment disclosed without departing from the spirit and scope of the invention and therefore it is intended that the specification and drawing be interpreted in an illustrative rather than a limiting sense.

10 What is claimed is:

1. A matrix magazine for a linecasting machine wherein in the matrix escapement mechanism is mounted on the machine and cooperates with the magazine when the magazine is placed on the machine, said magazine comprising a top plate and a bottom plate separated by a pair of side bars and grooved in their adjacent faces to form guiding channels for the matrices, an intermediate bar and an end bar spaced from the lower end of the bottom plate and secured to the side bars, said bars having grooves aligned with the grooves of said bottom plate to guide the matrices, and a matrix blocking means secured to the side bars at the lower end of said top plate having a manually operated member for locking the matrices in the magazine when the magazine is removed from the machine, characterized in that said top plate is longer than said bottom plate and extends adjacent said intermediate bar whereby said top plate and said intermediate bar support a matrix in upright position prior to its release from the magazine.
2. A matrix magazine for a linecasting machine according to claim 1, including a plurality of cross bars and a longitudinal center bar secured to the bottom plate of the magazine characterized in that the top and the bottom plates, the side bars, the intermediate and the end bars, the cross bars and the center bar are all formed of aluminum.
3. A matrix magazine for a linecasting machine according to claim 1, wherein the matrix blocking means includes an escapement cover secured to the side bars adjacent the lower end of the top plate of the magazine, a matrix locking bar housed by said cover, a first latching means and a second latching means, both of which must be actuated before the matrix locking bar can be moved to an unblocking position, characterized in that each of said latching means is integral with the free arm of a U-shaped spring that is secured to the escapement cover and cooperates with a pin projecting from the locking bar.

4. A matrix magazine for a linecasting machine according to claim 1 wherein the matrix blocking means includes an escapement cover secured to the side bars adjacent the lower end of the top plate of the magazine, a matrix locking bar housed by said cover, and means responsive to movement of the locking bar transverse to the magazine for moving said bar downwardly into a matrix locking position and then rearwardly to move the matrices away from the pawls of the escapement mechanism.
